Primary Examiner — T. Chase Nelson*Assistant Examiner* — Ania Aman(74) *Attorney, Agent, or Firm* — Kirton McConkie; Brian Tucker(57) **CLAIM**

The ornamental design for a candle warmer, as shown and described.

DESCRIPTION

FIG. 1 is a front perspective view thereof;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan thereof; and,

FIG. 7 is a bottom plan thereof.

The light bulb and light fixture contained within the candle warmer, the electric cord, and cord openings and round support structure on the bottom of the candle warmer are shown in broken lines and form no part of the claimed design.

1 Claim, 4 Drawing Sheets**FIG. 1**
